UNITED STATES PATENT OFFICE.

JOHN E. KENNEDY AND HARRY L. KENNEDY, OF INDIANAPOLIS, INDIANA,
ASSIGNORS TO THE KENNEDY MANUFACTURING COMPANY, OF SAME
PLACE.

GAS-METER.

SPECIFICATION forming part of Letters Patent No. 623,911, dated April 25, 1899.

Application filed November 18, 1897. Serial No. 658,978. (No model.)

To all whom it may concern:

Be it known that we, JOHN E. KENNEDY and HARRY L. KENNEDY, citizens of the United States, residing at Indianapolis, in the county 5 of Marion and State of Indiana, have invented certain new and useful Improvements in Gas-Meters, of which the following is a specification.

The object of our said invention is to improve the construction and arrangement of the mechanism of gas-meters and to provide means whereby such mechanism may be located upon the outside of the meter-body, where it will be free from the deleterious effects of the gas.

A gas-meter embodying our said invention will be first fully described and the novel features thereof then pointed out in the claims.

Referring to the accompanying drawings, 20 which are made a part hereof and on which similar letters and numerals of reference indicate similar parts, Figure 1 is a front elevation of a gas-meter embodying our present invention; Fig. 2, a vertical sectional view thereof as seen when looking in the direction indicated by the arrows from the dotted line 2 2 in Fig. 1; Fig. 3, a front elevation of the valve-controlling and registering mechanism and immediately adjacent parts on an enlarged scale; Fig. 4, a top plan of the portions shown in Fig. 3, the registering mechanism being broken away to show the valve-controlling mechanism more plainly; Fig. 5, a central vertical sectional view as seen from the dotted line 5 5 in Fig. 3; Fig. 6, a detail rear elevation of the connection between the valve-controlling and the registering mechanisms as seen from the dotted line 6 6 in Fig. 5; Fig. 7, a perspective view of the vertical shaft and the 30 bell-crank lever thereon; Fig. 8, an interior view showing especially the valves and passage-ways as seen when looking toward the left from the dotted line 8 8 in Fig. 2; Fig. 9, a horizontal sectional view as seen when looking downwardly from the dotted line 9 9 in Fig. 8; Fig. 10, a similar view as seen from the dotted line 10 10; Fig. 11, a view similar to a portion of Fig. 9 on an enlarged scale, and Fig. 12 a detail sectional view on the dotted 45 line 12 12 in Fig. 8.

The body B of the gas-meter is preferably, as is usual, composed of metal and divided into two chambers C C' by means of a flexible diaphragm D, secured therein in a substantially central position and having attached thereto on a portion of its surface a plate D', which is in turn rigidly mounted on a shaft S, which shaft is within a space provided therefor in one of the chambers and the ends of which project through stuffing-box bearings to the outside. There are the usual inlet and outlet pipes A A' to the meter, and the inlet-pipe A is adapted to discharge alternately into first one chamber and then the other, according to the position of the valves V, while the egress-pipe A' is adapted to discharge alternatively from one chamber and the other, according to the position of said valves, the arrangement being such that one chamber is being filled while the other is being emptied, and in this respect our gas-meter is not dissimilar, except in details of construction and arrangement by which the valve-openings are brought into convenient relation to our improved arrangement of valves, 65 from former gas-meters.

The valves V are mounted on a cross-arm carried on the lower end of a rock-shaft 1, which rock-shaft extends up through the outer casing of the meter to the outside, where 70 it bears upon its upper end a bell-crank lever 2. In order to effectually prevent the escape of gas around this rock-shaft 1, we have provided a peculiar bearing for said shaft. This bearing consists of a preferably cylindrical structure having suitable bearing-points for the shaft, as best shown in Figs. 3 and 5, with its lower end enlarged somewhat and containing a small diaphragm d, which is secured to the rim thereof and also secured 75 between collars on said shaft. This diaphragm is thin and flexible and is large enough so that it will not interfere with the slight rocking motion of the shaft, while at the same time effectually preventing the escape of any gas around said shaft.

The rearwardly-extending arm of the bell-crank lever 2 is connected by means of springs 3 3 to suitable points on a rocking frame 4, the pivot or pivot-shaft 5 whereof is directly 80 85 90 95 100

above the rock-shaft 1, so that the axial lines of said two shafts intersect. The transversely-extending arm of the bell-crank lever 2 has in turn a vertical portion 6, which extends up parallel with the axial line of the shaft 1 until it crosses one arm of the frame 4, and said extension has an engaging point 7 at or near its upper end and substantially in the same horizontal plane as the pivot-shaft 5 of the frame 4. Extending out from said pivot-shaft or from some other suitable point on or rigid with the frame 4 is an arm 8, which extends into the path of the projection 7.

15 The frame 4 is connected by means of a suitable link L with an arm S' on the rock-shaft S, which shaft is operated by the vibration of the main diaphragm D within the meter by means of the plate D', mounted thereon, as will be readily understood, especially by an examination of Fig. 5. As best shown in Fig. 6, the rocking frame 4 is connected by means of a slotted or bifurcated pitman P, straddling the scape-wheel shaft and carrying suitable pushing and pulling engaging fingers p p', which engage with the scape-wheel W of the ordinary clockwork-like registering mechanism of the meter. This clockwork-like mechanism being of the usual and well-known construction and arrangement and forming no part of our present invention need not be further described herein.

The valves V, as above stated, are carried by a cross-bar V', which in turn is rigidly secured to the rock-shaft 1. They are positioned in small chambers near the side of and within the meter just below the register-operating mechanism, which small chambers have two openings, one leading in each direction and communicating, respectively, with the main chambers of the meter, and which have rims surrounding them, forming valve-seats. These openings are adapted to be alternatively opened and closed by said valves. As will be best understood by an inspection of Fig. 9, the gas flows through the pipe A into one of the chambers containing a valve V and thence into the chamber C or C', according to the position of said valve V. When the valve is in the position shown in Fig. 9, the flow is around, by means of the by-path at the same end of the meter, to the chamber C', and while said chamber C' is filling the chamber C is emptying through the valve at the other end of the meter, as will be readily understood. When the chamber C has been filled and the chamber C emptied, the register-operating mechanism has been shifted, as above described, and the valves shift position. 60 The gas will then flow directly from the small valve-chamber near the inner end of the pipe A into the chamber C, and the gas in the chamber C' will escape around by means of the by-path at the opposite end of the meter through the pipe A'. The direction of flow of the gas is shown by long curved arrows in Figs. 8 and 9.

The operation is as follows: The flow of gas pressing upon the main diaphragm D operates the rock-shaft S, which through its arm S' and the link L operates the rocking frame 4. The bell-crank lever 2 and the shaft 1 are held from moving throughout the greater portion of the movement of the frame 4 by means of the engagement of the point 7 with the arm 8. As said frame moves, however, the tension upon one of the springs 3 increases, while the other decreases, and when the movement has been completed the engaging point 7 escapes from the surface of the arm 8, and the springs being thus freed operate to suddenly rock the shaft 1 and shift the valves, and thus close the ingress-opening to one of the chambers in the meter, while opening the egress-opening thereto, at the same time opening the ingress-opening to the other chamber in the meter and closing the egress-opening thereto. The chamber which has just been filled then begins to empty, while the chamber which has just been emptied begins to fill, and the frame 4 is thereby given a movement in the other direction. The point 7 ascends on the opposite side of the arm 8 from that upon which it has descended, and, as before, it is held in position until the ascent is completed, when it escapes, and the reverse of the operation just described takes place.

Having thus fully described our said invention, what we claim as new, and desire to secure by Letters Patent, is—

1. The combination, in a gas-meter mechanism, of a rock-shaft having a cross-arm carrying the valves upon the lower end within a chamber of the meter, a bell-crank lever upon the upper end of said shaft outside the meter, a rocking frame the axis whereof is above and at right angles with said rock-shaft, spring connections between the rearwardly-extending arm of said bell-crank lever and suitable points at the ends of said frame, an engaging point on an extension of said bell-crank lever, and a detent-arm carried by and moving with said frame and extending into the path of said engaging point, whereby said bell-crank lever is held in one position until the full movement of said rocking frame is accomplished, whereupon it is permitted by the escape of said engaging point and caused by the operation of said springs to suddenly move and shift the position of the valves, substantially as set forth.

2. The combination, in a gas-meter, of the casing, a cylindrical structure mounted in said casing and having suitable bearing points for the rock-shaft 1, said rock-shaft mounted in said bearings to extend through said cylindrical structure from the inside to the outside of the meter, valves for controlling the flow of gas mounted on an arm carried by its inner end, registering mechanism connected to its outer end, and a flexible diaphragm joined both to said shaft and to said cylindrical structure by air-tight joints, substantially as set forth.

3. The combination, in a gas-meter, of the rock-shaft 1, a cross-bar V' thereon, valves V on said cross-bar, duplicate passages leading into the two main chambers of the meter 5 on the two sides of said valves and provided with suitable valve-seats, a bell-crank lever 2 on the upper end of the shaft 1, a rocking frame 4 the pivot-point whereof is at right angles with the rock-shaft 1, an arm 8 rigid with o said frame 4, a vertical portion 6 on said bell-crank lever having an engaging point 7 into the path whereof the arm 8 extends, springs 3 connecting the rearwardly-extending arm of the bell-crank lever and with suitable projections on the rocking frame 4, and a connection between said rocking frame 4 and the rock-shaft of the diaphragm in the meter, substantially as and for the purposes set forth.
- 20 4. The combination, in a gas-meter, of the two small valve-chambers within the body of the meter, a rock-shaft positioned between the said valve-chambers, a bar on said rock-

shaft carrying the valves, a rock-shaft extending through the meter to its outside along- 25 side the diaphragm, said diaphragm, a plate or arm rigidly secured to said rock-shaft and attached across said diaphragm, whereby its vibrations will rock said shaft, and connecting mechanism connecting the outside end of said rock-shaft with the rock-shaft carrying the valves, whereby said valves are alternately opened and closed by the vibration of said diaphragm and the gas thus admitted to and allowed to escape from the two main 30 35 chambers of the meter, substantially as set forth.

In witness whereof we have hereunto set our hands and seals, at Indianapolis, Indiana, this 16th day of November, A. D. 1897.
